CLAIM

The ornamental design for candelabra, substantially as shown and described.

DESCRIPTION

FIG. 1 is a side perspective view of a candelabra showing
my new design;

FIG. 2 is an opposite side perspective view thereof;

FIG. 3 is a top plan view thereof;

FIG. 4 is a side elevational view thereof, the opposite side being a mirror image;

FIG. 5 is an end elevational view thereof, the opposite end being a mirror image.
